UNITED STATES PATENT OFFICE.

HANS MARTIN HANSON, OF SAWYER, WISCONSIN.

BALING-PRESS.

1,249,750.

Specification of Letters Patent. Patented Dec. 11, 1917.

Application filed February 8, 1917. Serial No. 147,352.

To all whom it may concern:

Be it known that I, HANS M. HANSON, a citizen of the United States, residing at Sawyer, in the county of Door and State of 5 Wisconsin, have invented certain new and useful Improvements in Baling-Presses, of which the following is a specification.

My invention relates to baling presses, and has for one of its objects the provision 10 of a simple and efficient baling press adapted for use in baling hay, straw, cotton, excelsior, and the like.

A further object is the provision of a press of the character mentioned in which the 15 compressor head is adapted to do effective work in both directions of its reciprocatory movement in order to effect greater economy in operation.

A still further object is the provision of 20 simple and efficient operating means for operating the compressor head of the press. Other objects will appear hereinafter.

An embodiment of my invention is shown 25 in the accompanying drawing, forming a part of this specification, and in which—

Figure 1 is a longitudinal section taken through a press embodying my invention; and

Fig. 2 is an enlarged section taken on line 30 2—2 of Fig. 1.

Referring more particularly to the drawing, I have shown a casing 5, inclosing a compressor chamber 6. Any desired form of compressor chamber and casing may be 35 provided. I have shown one elongated with a feed opening 7 near its central top portion, and a discharge opening 8 at one end, and a discharge opening 9 at the other end. The feed opening 7 is provided with a hopper 40 per 10 to facilitate feeding the materials to be baled into the compressor chamber 6. The materials utilized in forming the casing 5 and hopper 10 may be of any materials desirable, in either metal or wood, or a combination of both.

In the compressor chamber 6 I have indicated a compressor head 11 adapted to be moved reciprocably back and forth in the chamber 6 under the feed opening 7 in such 50 a manner that materials to be baled may be fed into the opening 7 alternately on each side of the head. This will be obvious upon reference to the full line and dotted line positions of the head 11 in Fig. 1. The head 55 11 is provided with one or more portions 12 which extend downwardly through slots 13

in floor 5' of the casing 5. In Fig. 2 I have indicated two of the members 12, but it will be understood that as many as is desirable may be used. The floor 5' will be provided 60 with sufficient slots 13 to accommodate the desired number of portions 12. The portions 12 extend sufficiently far through the slots 13 to engage the upper side of a sliding member 14 and are secured to the latter by 65 cap screws 15, or their equivalent. The slide member 14 is shown as being mounted in guideways 16 provided in frame member 17 at the bottom of the casing 5. The arrangement is such that the member 14 slides 70 longitudinally of the casing 5 and moves the head 11 back and forth under the hopper 10 and feed opening 7.

The frame 17 extends sufficiently far from the discharge opening 8 of the casing to provide 75 sufficient room between the opening 8 and driving mechanism of member 14 to permit the bales of material to be taken from the machine. The frame 17 carries upright frame members 18 in which is 80 mounted the driving mechanism of member 14. The member 14 is provided with a set of rack teeth 19 which mesh with mutilated gears 20 and 21. The gears 20 and 21 are preferably rotated in opposite directions 85 and arranged with relation to each other so that one gear moves the member 14 in one direction, and the other gear moves such member in the opposite direction. In the device shown the gears 20 and 21 are mounted 90 on shafts 22 in the frame member 18, and the shafts connected together through a train of gears 23. One of the shafts of gears 23 has a large gear 24, which meshes 95 with a pinion 25, and the latter connected 95 through a shaft 26 with a driving pulley 27, which in turn is connected to any suitable source of power, not shown, by means of an endless belt 28. The means for driving the mutilated gears 20 and 21 may be varied as 100 desired. In Fig. 1, mutilated gear 20 is shown as just completing its operation on the member 14 to move the head 11 to its left-hand terminal of movement. As soon as the gear 20 rotates sufficiently to free it 105 self from the rack teeth 19, the teeth of gear 21 are adapted to engage the rack teeth 19 and move the member 14 in the opposite direction until head 11 comes to its dotted line position shown in this figure.

I have shown a form of feeding mechanism for feeding material automatically into

the compressor chamber 6. This form of device comprises a feeder member 29 mounted on the free end of an arm 30, which is fixed on a shaft 31, and the latter mounted on a 5 suitable portion of the casing 5. At one end of shaft 31 I provide an arm 32 with a slot 33 therein. A shaft 34, having a crank arm 35 therein is also mounted on a suitable portion of the casing with the crank arm 35 10 engaging the slot 33 to oscillate arms 32 and 33 to move the feeding member from its full line to its dotted line positions in Fig. 1. The shaft 34 is connected by means of a 15 sprocket gearing 36 with a suitable portion of the driving means, such as a shaft 22, so that the shaft 34 will rotate at the ratio of 2 to 1 with shaft 22. With this arrangement the feeder member 29 will be caused to 20 pass through two cycles of its movement while the shaft 22 rotates once. This will cause the member 29 to feed material through opening 7 into the casing 5 on each 25 side of the head 11 to cause the device to compress the material into bales in both ends thereof. This will provide a double baling machine.

I claim:—

1. A baling press comprising a casing 30 enclosing an elongated compressor chamber; a sliding member mounted for movements longitudinally of the compressor chamber; a head in the compressor chamber connected with said member; rack teeth on said member; and a plurality of mutilated driving 35 gears meshing with said rack teeth, each of said gears being adapted to move said member in one direction.

2. A baling press comprising a casing 40 enclosing an elongated compressor chamber; a sliding member mounted for movements longitudinally of the compressor chamber; a head in the compressor chamber connected with said member; rack teeth on said member; and two mutilated driving gears adapted 45 to rotate in opposite directions and mesh with said rack teeth, one at a time.

Copies of this patent may be obtained for five cents each, by addressing the "Commissioner of Patents, Washington, D. C."

3. A baling press comprising a casing enclosing an elongated compressor chamber; a sliding member mounted adjacent the compressor chamber; a head in the compressor chamber connected with said member; rack teeth on said member; two mutilated gears adapted to mesh with said rack teeth, one at a time; a train of gearing connecting said mutilated gears and adapted to 50 drive the latter in opposite directions; and a driving connection connected with said train of gearing.

4. A baling press comprising an elongated compressor casing having a feed opening 60 therein; a member slidably mounted in the casing; a compressor head in the casing connected with said member; rack teeth on said member; two mutilated gears adapted to mesh, one at a time, with the rack teeth for 65 reciprocating said member; and a feed arm connected with the mutilated gears and adapted to reach through said feed opening while each of the mutilated gears is meshing with the rack teeth.

5. A baling press comprising an elongated compressor casing having a feed opening 70 therein; a member slidably mounted in said casing; a compressor head in the casing and connected with said member; rack teeth on 75 said member; two mutilated gears adapted to mesh, one at a time, with said rack teeth; a train of gears connecting said mutilated gears and adapted to drive the latter in opposite directions; an oscillatory feed member 80 mounted on the casing; a driving connection between the feed member and said train of gearing adapted to move said member through a complete cycle of its movement while each mutilated gear is in mesh 85 with said rack teeth; and a driving connection connected with said train of gearing.

In testimony whereof I have signed my name to this specification on this 26th day of January, A. D. 1917.

HANS MARTIN HANSON.
